Primary Examiner — Michelle E. Wilson*Assistant Examiner* — Clesse Moore, Jr.(74) Attorney, Agent, or Firm — Alston & Bird LLP(57) CLAIM

We claim the ornamental design for a swimsuit, as shown and described.

DESCRIPTION

FIG. 1 is a front elevation view of a swimsuit showing our new design;

FIG. 2 is a rear elevation view thereof;

FIG. 3 is a perspective view thereof, shown worn on a model;

FIG. 4 is another perspective view thereof; and

FIG. 5 is another rear elevation view thereof.

FIG. 6 is a front elevation view of another embodiment of a swimsuit showing our new design; and

FIG. 7 is a rear elevation view thereof.

FIG. 8 is a front elevation view of yet another embodiment of a swimsuit showing our new design; and,

FIG. 9 is a rear elevation view thereof.

The broken lines in FIGS. 1-9 illustrate features of the swimsuit that form no part of the claimed design.

1 Claim, 7 Drawing Sheets(56)
